UNITED STATES PATENT OFFICE.

MATTHIAS BROCK, OF BOSTON, MASSACHUSETTS, ASSIGNOR, BY MESNE ASSIGNMENTS,
TO UNITED SHOE MACHINERY CORPORATION, OF PATERSON, NEW JERSEY, A COR-
PORATION OF NEW JERSEY.

END-LASTING MECHANISM.

1,261,484.

Specification of Letters Patent.

Patented Apr. 2, 1918.

Application filed July 7, 1915. Serial No. 38,552.

To all whom it may concern:

Be it known that I, MATTHIAS BROCK, a citizen of the United States, residing at Boston, in the county of Suffolk and State of Massachusetts, have invented certain Improvements in End-Lasting Mechanism, of which the following description, in connection with the accompanying drawings, is a specification, like reference characters on the drawings indicating like parts in the several figures.

This invention relates to lasting machines and particularly to end lasting mechanism, being herein shown for illustrative purposes 15 as embodied in mechanism for lasting the heel seats of turn shoes after the shoes have been sewed.

Under some conditions in shoe manufacturing it is desirable to have end lasting 20 wipers extend longitudinally of the shoe for distances which vary in different shoes, and in a co-pending application Ser. No. 36,736, filed June 28, 1915, is shown a wiper mechanism in which wiper members are adjustable lengthwise. In the mechanism illustrated in that application means is provided for effecting an adjustment of the side members of a two-part wiper and for retaining the adjustment. A feature of this 25 invention consists in wipers which are automatically adjustable lengthwise. This feature of the present invention is shown as embodied in mechanism which comprises means by which the wipers are automatically 30 adjusted for each shoe and are returned automatically to a full length position after each shoe has been withdrawn from the machine. The illustrated embodiment of the 35 invention is shown in the drawings as used 40 in lasting the heel seats of turn shoes. When so used the adjustment of the wipers lengthwise to meet the requirements of the work is effected automatically during the presentation of the work. The wipers shown 45 comprise endwise movable side members, as in said application, and these side members have connections with parts which extend into position to be engaged by the upwardly and forwardly turned heel seat portion of 50 the turn shoe sole as the shoe is jacked backwardly into the heel lasting mechanism. The sole thus forces the wipers backwardly to the length required for the particular shoe which is presented to the machine, and

when the wipers are thereafter operated 55 they last the full length of heel seat exposed for lasting in that shoe. As shown the wipers at the two sides of the shoe are independently movable so that each wiper is adjusted automatically to the length of the 60 heel seat on the side of the shoe upon which that wiper is to operate.

This and other features of the invention will be made clear from the following description of the illustrative embodiment of 65 the invention, considered in connection with the accompanying drawings, and the invention will then be particularly pointed out in the claims.

Figure 1 of the drawings is a plan view 70 of a heel seat lasting mechanism embodying this invention and shows a turn shoe applied to the heel pin of the machine.

Fig. 2 is a similar view showing the wipers partially closed to present the wiper 75 feelers in position for adjustment of the wipers to be effected when the shoe is moved backwardly into position to be operated upon.

Fig. 3 shows the shoe jacked back into the 80 machine and the wipers adjusted for the length of the heel seat.

The opposed heel seat wipers each comprise a rear end member 2 and a side member 4. Members 2 are shown as pivotally 85 connected together and as each connected near its outer edge to a link 6 which extends from a cross-head 8 on a plunger 9 operated by a hand lever 10. The wiper members 2 have cam slots 12 which coöperate with relatively fixed studs 14 and they also have their outer edges in engagement with the side walls of the wiper recess in the wiper carrier 13. By these guiding devices the wiper members 2 are caused to advance and close inwardly over the rear end of the heel seat when the hand lever 10 is moved toward the left in the drawings. Each side member 4 is mounted in its co-operating end member to partake of the inward closing movement of member 2 but is restrained by a stud 15 from partaking of the advancing movement of the member 2. The stud 15 extends upwardly into a transverse slot in a slide bar 16 which is guided for movement longitudinally of the machine in the wiper carrier 13. The slide bar 16 has a stud which stands in a slot in the wiper

carrier and is pressed forwardly by a spring plunger 18. The side members 4 each supports at its free end a feeler 20 which extends inwardly therefrom toward the shoe 5 and is shown as adjustably positioned transversely of the shoe by a screw 21. A spring 22 encircles the wiper operating plunger 9 and holds the wipers normally in the position shown in Fig. 2. The heel pin 24 upon 10 which the last is supported has a rack and pinion connection, not shown, with a hand wheel 25 by which the shoe is drawn backwardly into the machine.

In the use of the machine the wipers are 15 spread by moving the hand lever 10 in the direction of the arrow, Fig. 1, and the shoe is applied to the heel pin 24, after which the spring 22 restores the wipers to the position shown in Fig. 2 in which the feelers 20 are in the path which the shoe will follow in being presented in position to be lasted. The hand wheel is then operated 25 to draw the shoe backwardly into the machine and through the contact of the upturned heel seat portion of the sole of a turn shoe, as seen in Fig. 3, with the feelers 20 serves to adjust the wipers for the length of the heel seat of the shoe which is to be lasted, this being effected by the pressure of 30 the turned back end of the sole sliding wiper members 4 backwardly against the pressure of the spring plungers 18 as shown in Fig. 3. The shoe is then lasted by usual operation of the wipers over its heel seat 35 and after the upper has been tacked in lasted position the wipers are retracted and the shoe unjacked and removed from the heel pin.

Having explained the nature of this invention and described an illustrative embodiment thereof, I claim as new and desire to secure by Letters Patent of the United States:—

1. In an end lasting mechanism, end embracing wipers, and means for supporting the wipers constructed and arranged to permit adjustment of the wipers by pressure of a shoe part to change their effective length.

2. In an end lasting mechanism, end embracing wipers, and means for supporting the wipers constructed and arranged to permit movement of the wipers automatically responsive to pressure of a shoe part to adjust the extent of their acting edges lengthwise of the shoe.

3. In an end lasting mechanism, end embracing wipers, and means for supporting said wipers constructed and arranged to permit independent adjustment of the 60 wipers lengthwise of the shoe responsive to engagement of the wipers with portions of the shoe at opposite sides of the shoe.

4. In an end lasting mechanism, the combination with wiper operating mechanism, 65 of end embracing wipers each comprising

an end member and a side member which is movable lengthwise relatively to the end member, and a spring for holding the members yieldingly extended.

5. In an end lasting mechanism, the combination with wiper operating mechanism, 70 of end embracing wipers each comprising an end member and a side member which are relatively movable to vary the length of the wipers, means for extending the 75 wipers, and means arranged for engagement with the shoe for adjusting the wipers to the requirements of the shoe.

6. In an end lasting mechanism, the combination with wiper operating mechanism, 80 of end embracing wipers constructed and arranged for adjustment lengthwise of the shoe, and means arranged for engagement with the shoe to effect the adjustment.

7. In an end lasting mechanism, the combination with wiper operating mechanism, 85 of end embracing wipers which are extensible independently of one another, and devices arranged for engagement with the shoe to effect adjustment of the wipers to meet 90 the requirements of the opposite sides of the shoe end.

8. In an end lasting mechanism, the combination with wiper operating mechanism, 95 of end embracing wipers arranged for adjustment by the shoe to shorten their effective length, and means for returning the wipers automatically to their full length after their operation.

9. In a heel seat lasting mechanism, the 100 combination with end embracing wipers, of feelers projecting from the end portions of the wipers into position for engagement with the upturned heel seat end of a turn shoe sole for relatively positioning the 105 wipers and the shoe, and means for operating the wipers.

10. In a heel seat lasting mechanism, the combination with end embracing wipers constructed and arranged for positioning 110 movement lengthwise, of abutment faces on the end portions of the wipers for engagement with the upturned heel seat end of a turn shoe sole, and means for relatively moving the shoe and said wipers to position 115 the wipers lengthwise for the shoe which is to be operated upon.

11. In a heel seat lasting mechanism, the combination with end embracing wipers each of which comprises a rear end member and a side member relatively movable longitudinally and normally occupying extended relation, of abutment faces on the front ends of the wipers for engagement with the shoe to adjust the length of the 125 wipers to the requirements of the shoe.

12. In a heel seat lasting mechanism, the combination with end embracing wipers which are adjustable in length, of shoe positioning means, and means operated auto- 130

matically by force transmitted from the shoe positioning means through the shoe to adjust the length of the wipers.

13. In a heel seat lasting mechanism, the combination with end embracing wipers which are adjustable in length and have on their ends abutment faces for engagement with the upturned end of a turn shoe sole, of means for moving the shoe endwise into position to be lasted and for automatically adjusting the length of the wipers during such movement.

14. In an end lasting mechanism, the combination with wiper operating mechanism, of wipers which comprise endwise adjustable side members, feelers extending into position for engagement with the shoe at the inner end of the portion which is to be lasted, and connections between the feelers and said wiper side members to effect adjustment of said members in accordance with the length of the portion of the shoe end to be lasted.

15. In an end lasting mechanism, the combination with wiper operating mechanism, of wipers which comprise endwise adjustable side members, and means connected with said side members and extending into position to be engaged by the upwardly and forwardly turned heel seat portion of the sole of a turn shoe as the shoe is jacked backwardly into the heel lasting mechanism.

16. In an end lasting mechanism, the combination with wiper operating mechanism, of end embracing wipers each comprising an end member and a side member which are automatically adjustable relatively to vary the effective length of the wiper.

17. In an end lasting mechanism, the combination with wiper operating mechanism, of wipers, and means by which the wipers

are automatically adjusted in length for each shoe and are returned automatically to full length position after each shoe has been withdrawn from the mechanism.

45

18. In an end lasting mechanism, the combination with end embracing wipers, abutments on the ends of the wipers, a spring for holding the wipers with the abutments in position for engagement with the shoe, and operating means for retracting the abutments to facilitate the insertion of the shoe into the machine and for operating the wipers to last the end of the shoe.

50

19. In an end lasting mechanism, the combination with end embracing wipers, of operating means for advancing and retracting the wipers, and a spring arranged to hold the wipers normally in a partially advanced position.

55

20. In an end lasting mechanism, the combination with end embracing wipers, of a hand lever and a plunger connected with the wipers for advancing and retracting the wipers, and a spring on the plunger arranged to return the wipers to a partially advanced position after they have been retracted.

60

21. In an end lasting mechanism, the combination with end embracing wipers, and means for jacking the shoe back into position to be operated upon by the wipers, said wipers being constructed and arranged for lengthwise extension, of means for holding them extended, and means arranged for engagement by the shoe during its backward movement to adjust the wipers lengthwise for that shoe.

65

In testimony whereof I have signed my name to this specification.

MATTHIAS BROCK.
